US008267196B2

(12) **United States Patent**
Hall et al.

(10) **Patent No.:** **US 8,267,196 B2**
(45) **Date of Patent:** **Sep. 18, 2012**

(54) **FLOW GUIDE ACTUATION**

- (75) Inventors: **David R. Hall**, Provo, UT (US); **Scott Dahlgren**, Alpine, UT (US); **Paula Turner**, Pleasant Grove, UT (US); **Christopher Durrand**, Pleasant Grove, UT (US); **Jonathan Marshall**, Provo, UT (US)
- (73) Assignee: **Schlumberger Technology Corporation**, Houston, TX (US)
- (*) Notice: Subject to any disclaimer, the term of this patent is extended or adjusted under 35 U.S.C. 154(b) by 232 days.

(21) Appl. No.: **12/473,473**

(22) Filed: **May 28, 2009**

(65) **Prior Publication Data**

US 2009/0236148 A1 Sep. 24, 2009

Related U.S. Application Data

- (63) Continuation of application No. 12/473,444, filed on May 28, 2009, which is a continuation-in-part of application No. 12/262,372, filed on Oct. 31, 2008, now Pat. No. 7,730,972, which is a continuation-in-part of application No. 12/178,467, filed on Jul. 23, 2008, now Pat. No. 7,730,975, which is a continuation-in-part of application No. 12/039,608, filed on Feb. 28, 2008, now Pat. No. 7,762,353, which is a continuation-in-part of application No. 12/037,682, filed on Feb. 26, 2008, now Pat. No. 7,624,824, which is a continuation-in-part of application No. 12/019,782, filed on Jan. 25, 2008, now Pat. No. 7,617,886, which is a continuation-in-part of application No. 11/837,321, filed on Aug. 10, 2007, now Pat. No. 7,559,379, which is a continuation-in-part of application No. 11/750,700, filed on May 18, 2007, now Pat. No. 7,549,489, which is a continuation-in-part of application No. 11/737,034, filed on Apr. 18, 2007, now Pat. No. 7,503,405, which is a continuation-in-part of application No. 11/686,638, filed on Mar. 15, 2007, now Pat. No. 7,424,922, which is a continuation-in-part of application No. 11/680,997, filed on Mar. 1, 2007, now Pat. No.

7,419,016, which is a continuation-in-part of application No. 11/673,872, filed on Feb. 12, 2007, now Pat. No. 7,484,576, which is a continuation-in-part of application No. 11/611,310, filed on Dec. 15, 2006, now Pat. No. 7,600,586, application No. 12/473,473, which is a continuation-in-part of application No. 11/278,935, filed on Apr. 6, 2006, now Pat. No. 7,426,968, which is a continuation-in-part of application No. 11/277,394, filed on Mar. 24, 2006, now Pat. No. 7,398,837, which is a continuation-in-part of application No. 11/277,380, filed on Mar. 24, 2006, now Pat. No. 7,337,858, which is a continuation-in-part of application No. 11/306,976, filed on Jan. 18, 2006, now Pat. No. 7,360,610, which is a continuation-in-part of application No. 11/306,307, filed on Dec. 22, 2005, now Pat. No. 7,225,886, which is a continuation-in-part of application No. 11/306,022, filed on Dec. 14, 2005, now Pat. No. 7,198,119, which is a continuation-in-part of application No. 11/164,391, filed on Nov. 21, 2005, now Pat. No. 7,270,196, application No. 12/473,473, which is a continuation-in-part of application No. 11/555,334, filed on Nov. 1, 2006, now Pat. No. 7,419,018.

(57) **ABSTRACT**

In one aspect of the present invention, a downhole drill string assembly comprises a bore there through to receive drilling fluid. A turbine may be disposed within the bore and exposed to the drilling fluid. At least one flow guide may be disposed within the bore and exposed to the drilling fluid wherein the flow guide acts to redirect the flow of the drilling fluid across the turbine. The flow guide may be adjusted by an actuator. Adjustments to the flow guide may be controlled by a down-hole telemetry system, a processing unit, a control loop, or any combination thereof. In various embodiments the turbine may comprise rotatable turbine blades.

This patent application is a continuation of U.S. patent application Ser. No. 12/473,444 filed on May 28, 2009 which is a continuation-in-part of U.S. patent application Ser. No. 12/262,372 filed on Oct. 31, 2008 and which is now U.S. Pat. No. 7,730,972 issued on Jun. 8, 2010, which is a continuation-in-part of U.S. patent application Ser. No. 12/178,467 filed on Jul. 23, 2008 and which is now U.S. Pat. No. 7,730,975 issued on Jun. 8, 2010, which is a continuation-in-part of U.S. patent application Ser. No. 12/039,608 filed on Feb. 28, 2008 and which is now U.S. Pat. No. 7,762,353 issued on Jul. 27, 2010, which is a continuation-in-part of U.S. patent application Ser. No. 12/037,682 filed on Feb. 26, 2008 and which is now U.S. Pat. No. 7,624,824 issued on Dec. 1, 2009, which is a continuation-in-part of U.S. patent application Ser. No. 12/019,782 filed on Jan. 25, 2008 and which is now U.S. Pat. No. 7,617,886, which is a continuation-in-part of U.S. patent application Ser. No. 11/837,321 filed on Aug. 10, 2007 and which is now U.S. Pat. No. 7,559,379, which is a continuation-in-part of U.S. patent application Ser. No. 11/750,700 filed on May 18, 2007 and which is now U.S. Pat. No. 7,549,489 issued on Jun. 23, 2009, which is a continuation-in-part of U.S. patent application Ser. No. 11/737,034 filed on Apr. 18, 2007 and which is now U.S. Pat. No. 7,503,405 issued on Mar. 17, 2009, which is a continuation-in-part of U.S. patent application Ser. No. 11/686,638 filed on Mar. 15, 2007 and which is now U.S. Pat. No. 7,424,922 issued on Sep. 16, 2008, which is a continuation-in-part of U.S. patent application Ser. No. 11/680,997 filed on Mar. 1, 2007 and which is now U.S. Pat. No. 7,419,016 issued on Sep. 2, 2008, which is a continuation-in-part of U.S. patent application Ser. No. 11/673,872 filed on Feb. 12, 2007 and which is now U.S. Pat. No. 7,484,576 issued on Feb. 3, 2009, which is a continuation-in-part of U.S. patent application Ser. No. 11/611,310 filed on Dec. 15, 2006 and which is now U.S. Pat. No. 7,600,586 issued on Oct. 13, 2009.

U.S. patent application Ser. No. 12/039,608 is also a continuation-in-part of U.S. patent application Ser. No. 11/278,935 filed on Apr. 6, 2006 and which is now U.S. Pat. No. 7,426,968 issued on Sep. 23, 2008, which is a continuation-in-part of U.S. patent application Ser. No. 11/277,394 filed on Mar. 24, 2006 and which is now U.S. Pat. No. 7,398,837 issued on Jul. 15, 2008, which is a continuation-in-part of U.S. patent application Ser. No. 11/277,380 filed on Mar. 24, 2006 and which is now U.S. Pat. No. 7,337,858 issued on March 4, 2008, which is a continuation-in-part of U.S. patent application Ser. No. 11/306,976 filed on Jan. 18, 2006 and which is now U.S. Patent No. 7,360,610 issued on Apr. 22, 2008, which is a continuation-in-part of U.S. patent application Ser. No. 11/306,307 filed on Dec. 22, 2005 and which is now U.S. Pat. No. 7,225,886 issued on Jun. 5, 2007, which is a continuation-in-part of U.S. patent application Ser. No. 11/306,022 filed on Dec. 14, 2005 and which is now U.S. Pat. No. 7,198,119 issued on Apr. 3, 2007, which is a continuation-in-part of U.S. patent application Ser. No. 11/164,391 filed on Nov. 21, 2005 and which is now U.S. Pat. No. 7,270,196 issued on Sep. 18, 2007.

U.S. patent application Ser. No. 12/039,608 is also a continuation-in-part of U.S. patent application Ser. No. 11/555,334 filed on Nov. 1, 2006 and which is now U.S. Pat. No.

7,419,018 issued on Sep. 2, 2008. All of these applications are herein incorporated by reference in their entirety.

BACKGROUND

5

This invention relates to the field of downhole turbines used in drilling. More Specifically, the invention relates to controlling the rotational velocity of downhole turbines.

Previous attempts at controlling downhole turbine speed 10 were performed by diverting a portion of the drilling fluid away from the turbine. It was believed that the diversion of drilling fluid away from the turbine results in less torque on the turbine itself. However, this technique may also require the additional expense of having to over design the turbine to 15 ensure that sufficient torque is delivered when fluid flow is restricted.

U.S. Pat. No. 5,626,200 to Gilbert et al., which is herein incorporated by reference for all that it contains, discloses a logging-while-drilling tool for use in a wellbore in which a 20 well fluid is circulated into the wellbore through a hollow drill string. In addition to measurement electronics, the tool includes an alternator for providing power to the electronics, and a turbine for driving the alternator. The turbine blades are driven by the well fluid introduced into the hollow drill string. 25 The tool also includes a deflector to deflect a portion of the well fluid away from the turbine blades.

U.S. Pat. No. 5,839,508 to Tubel et al., which is herein incorporated by reference for all that it contains, discloses an electrical generating apparatus which connects to the production 30 tubing. In a preferred embodiment, this apparatus includes a housing having a primary flow passageway in communication with the production tubing. The housing also includes a laterally displaced side passageway communicating with the primary flow passageway such that production fluid passes upwardly towards the surface through the primary and side passageways. A flow diverter may be positioned in the housing to divert a variable amount of the production fluid from the production tubing and into the side 35 passageway. In accordance with an important feature of this invention, an electrical generator is located at least partially in or along the side passageway. The electrical generator generates electricity through the interaction of the flowing production fluid.

U.S. Pat. No. 4,211,291 to Kellner, which is herein incorporated by reference for all it contains, discloses a drill fluid 45 powered hydraulic system used for driving a shaft connected to a drill bit. The apparatus includes a hydraulic fluid powered motor actuated and controlled by hydraulic fluid. The hydraulic fluid is supplied to the hydraulic fluid powered motor through an intermediate drive system actuated by drill fluid. The intermediate drive system is provided with two rotary valves and two double sided accumulators. One of the rotary valves routes the hydraulic fluid to and from the accumulators from the drill fluid supply and from the accumulators to the 50 drill bit. The rotary valves are indexed by a gear system and Geneva drive connected to the motor or drill shaft. A heat exchanger is provided to cool the hydraulic fluid. The heat exchanger has one side of the exchange piped between the drill fluid inlet and the drill fluid rotary valve and the other side of the exchange piped between the hydraulic fluid side of the accumulators and the hydraulic fluid rotary valve.

U.S. Pat. No. 4,462,469 to Brown, which is herein incorporated by reference for all that it contains, discloses a motor for driving a rotary drilling bit within a well through which 60 mud is circulated during a drilling operation, with the motor being driven by a secondary fluid which is isolated from the circulating mud but derives energy therefrom to power the

motor. A pressure drop in the circulating mud across a choke in the drill string is utilized to cause motion of the secondary fluid through the motor. An instrument which is within the well and develops data to be transmitted to the surface of the earth controls the actuation of the motor between different operation conditions in correspondence with data signals produced by the instrument, and the resulting variations in torque in the drill string and/or the variations in torque in the drill string and/or the variations in circulating fluid pressure are sensed at the surface of the earth to control and produce a readout representative of the down hole data.

U.S. Pat. No. 5,098,258 to Barnetche-Gonzalez, which is herein incorporated by reference for all that it contains, discloses a multistage drag turbine assembly provided for use in a downhole motor, the drag turbine assembly comprising an outer sleeve and a central shaft positioned within the outer sleeve, the central shaft having a hollow center and a divider means extending longitudinally in the hollow center for forming first and second longitudinal channels therein. A stator is mounted on the shaft. The stator has a hub surrounding the shaft and a seal member fixed to the hub wherein the hub and the shaft each have first and second slot openings therein. A rotor comprising a rotor rim and a plurality of turbine blades mounted on the rotor rim is positioned within the outer sleeve for rotation therewith with respect to the stator such that a flow channel is formed in the outer sleeve between the turbine blades and the stator. A flow path is formed in the turbine assembly such that fluid flows through the turbine assembly, flows through the first longitudinal channel in the central shaft, through the first slot openings in the shaft and the stator hub, through the flow channel wherein the fluid contacts the edges of the turbine blades for causing a drag force thereon, and then through the second slot openings in the stator hub and the shaft into the second channel.

BRIEF SUMMARY

In one aspect of the present invention, a downhole drill string assembly has a bore formed therethrough formed to accept drilling fluid. The assembly also includes a turbine disposed within the bore. The turbine has at least one turbine blade and is in communication with a generator, a gear box, a steering assembly, a hammer element, a pulse telemetry device or any combination thereof.

The downhole drill string assembly further includes at least one flow guide disposed within the bore. The flow guide may be controlled by a feedback loop. The at least one flow guide may include a fin, an adjustable vein, a flexible surface, a pivot point or any combination thereof. The flow guide may be in communication with an actuator. The actuator may be a rack and pinion, a solenoid valve, an aspirator, a hydraulic piston, a flange, a spring, a pump, a motor, a plate, at least one gear, or a combination thereof.

In another aspect of embodiments of the present invention, a method for adjusting the rotation of a turbine is disclosed. This method comprises the steps of providing a downhole drill string assembly having a bore therethrough to receive drilling fluid, a turbine disposed within the bore and exposed to the drilling fluid, and at least one flow guide disposed within the bore and exposed to the drilling fluid. Then adjusting the flow guide to alter the flow of the drilling fluid, wherein the altered flow of the drilling fluid adjusts the rotation of the turbine.

The adjustment of the rotation of the turbine may comprise slowing down or speeding up of the rotational velocity of the turbine, or increasing or decreasing the rotational torque of the turbine. The adjustments may be controlled by a down-

hole telemetry system, a processing unit, a control loop, or any combination of the previous. The control loop may control the voltage output from a generator, a rotational velocity of the turbine, or a rotational torque from the turbine. The gain values of the control loop may be adjustable by an uphole computer and fed down to the turbine by a telemetry system or may be autonomously generated by prior programming against a preset target.

The assembly may further include a hammer disposed within the drill string and mechanically coupled to the turbine, wherein an actuation of the hammer is changed by adjusting the rotation of the turbine. The change in the actuation of the hammer may take the form of a change in frequency. This change in actuation may allow the hammer to be used to communicate uphole. The actuating hammer may be able to communicate through acoustic waves, vibrations of the drill string assembly, or changes in pressure created by the hammer impacting the formation or by the hammer impacting a surface within the drill string assembly. The turbine itself may also create a pressure pulse for use in communication or the turbine may actuate a valve to create a pressure pulse for use in communication.

BRIEF DESCRIPTION OF THE DRAWINGS

FIG. 1 is an orthogonal diagram of an embodiment of a drill string assembly suspended in a cross section of a bore hole.

FIG. 2 is a cross-sectional diagram of an embodiment of a drill string assembly.

FIG. 3 is a perspective diagram of an embodiment of a turbine, flow guide, and actuator.

FIG. 4a is another perspective diagram of an embodiment of a turbine, flow guide, and actuator.

FIG. 4b is another perspective diagram of an embodiment of a turbine, flow guide, and actuator.

FIG. 5 is another perspective diagram of an embodiment of a turbine, flow guide, and actuator.

FIG. 6 is a perspective diagram of an embodiment of a flow guide and actuator.

FIG. 7 is another perspective diagram of an embodiment of a turbine, flow guide, and actuator.

FIG. 8 is another perspective diagram of an embodiment of a turbine, flow guide, and actuator.

FIG. 9 is a cross-sectional diagram of an embodiment of a turbine, flow guide, and actuator.

FIG. 10a is another cross-sectional diagram of an embodiment of a turbine, flow guide, and actuator.

FIG. 10b is another cross-sectional diagram of an embodiment of a turbine, flow guide, and actuator.

FIG. 11 is another cross-sectional diagram of an embodiment of a turbine, flow guide, and actuator.

FIGS. 12a and 12b are side view diagrams of an embodiment of a turbine comprising dynamic turbine blades.

DETAILED DESCRIPTION

FIG. 1 is an orthogonal diagram of an embodiment of a drill string 100 suspended by a derrick 108 in a bore hole 102. A downhole drill string component having a drilling assembly 103 is located at a bottom of the bore hole 102 and includes a drill bit 104. As the drill bit 104 rotates downhole, the drill string 100 advances farther into a subterranean formations 105 having the bore hole 102. The drilling assembly 103 and/or downhole components may have data acquisition devices adapted to gather data that may be used identify a desirable formation 107 and to aid the drill string 100 in accessing the desirable formation 107. The data may be sent

to the surface via a transmission system to a data swivel 106. The data swivel 106 may send data and/or power to the drill string 100. U.S. Pat. No. 6,670,880 to Hall et al. which is herein incorporated by reference for all that it contains, discloses a telemetry system that may be compatible with the present invention; however, other forms of telemetry may also be compatible such as systems that include mud pulse systems, electromagnetic waves, radio waves, wired pipe, and/or short hop. The data swivel 106 may be connected to a processing unit 110 and/or additional surface equipment.

Referring now to FIG. 2, a drilling assembly 103A compatible with drill string 100 is illustrated. The drilling assembly 103A may have a jack element 202A. The jack element 202A aids in formation penetration and in steering the drill string. A first turbine 207A and a second turbine 240A may be located within a bore 208A formed in the drilling assembly 103A. The first turbine 207A or the second turbine 240A may be adapted for a variety of purposes including, but not limited to power generation, jack element actuation, steering, or hammer actuation.

In the embodiment of FIG. 2 the first turbine 207A is adapted to rotate the jack element 202A and the second turbine 240A is adapted to actuate a hammer element 234A. A gearbox 211A disposed in the bore 208A is adapted to transfer torque from the first turbine 207A to the jack element 202A. The rotational speed of the first turbine 207A is adjustable such that the rotational speed of the jack element 202A changes. The rotational speed of the second turbine 240A is adjustable such that the actuation of the hammer element 234A changes. A downhole processing unit 203A disposed within the bore 208A is in communication with a first actuator 204A and a second actuator 241A. In the embodiment of FIG. 2, the actuators 203A, 241A includes planetary gear systems 206A. The first actuator 204A in further communication with a first at least one flow guide 205A, and the second actuator 241A is in turn in communication with a second at least one flow guide 245A. The downhole processing unit 203A controls the actuators 204A, 245A independently such that the first at least one flow guides 205A and the second at least one flow guide 245A are manipulated causing the first turbine 207A and the second turbine 240A to change speeds independently.

Adjusting the second at least one flow guide 245A causes the second turbine 240A to change rotational speed thereby causing the frequency of the actuation of the hammer element 234A to change. Through the changing of the frequency of the actuation of the hammer element 234, uphole communication is possible. The communication signals may take the form of the hammer element 234A creating acoustic waves from an impact of the hammer element 234A on the formation, or the impact of the hammer element 234A on a surface 246A within the drill string assembly 103A. The communication signals may also take the form of a vibration of the tool string assembly 103A or pressure changes of a drilling fluid within the tool string assembly 103A caused by the hammer element's 234A actuation. An uphole sensor such as a geophone, a pressure sensor, or an acoustic sensor may be used to receive the communications uphole. Communication along the drill string may also take the form of pressure pulses created by changing the rotational speed of the first turbine 207A and/or the second turbine 240A, or by rotating a valve with the first turbine 207A of the second turbine 240A.

The processing unit 203A may also be in communication with a downhole telemetry system, such that an uphole operator can send commands to the first actuator 204A and the second actuator 241A. The processing unit 203A may also have a feedback loop that controls the actuator 204A. The

feedback loop may be controlled by an output of the first turbine 207A and/or the second turbine 240A. The controlling output of the first turbine 207A and/or the second turbine 240A may include a voltage output from a generator (not shown) that is powered by the first turbine 207A or the second turbine 240A respectively, a desired rotational velocity of first turbine 207A or the second turbine 240A respectively, or a desired rotational torque of the first turbine 207A or the second turbine 240A respectively. The controlling gains of the feedback loop and other aspects of the feedback loop may be adjustable by an uphole computer.

FIG. 3 is a perspective diagram of a portion of an embodiment of a drilling assembly 103B. In this figure a turbine 207B, an actuator 204B and at least one flow guide 205B are depicted. The actuator 204B in this embodiment is a plate 301B. The plate 301B is disposed axially around the drilling assembly 103B. The plate 301B includes pass through slots 302B adapted to allow fluid to flow through the plate 301B. The plate 301B includes attachment points 303B adapted to attach to at least one flow guide 205B. The at least one flow guide 205B has a clamp 305B.

The clamp 305B is adapted to attach to the drill assembly 103B through a connection point 304B. The flow guide 205B includes a flexible vane 306B.

As drilling fluid travels down the drill string and enters into the drilling assembly 103B the turbine 207B may begin to rotate. The rotational force generated by the turbine 207B may be used for a variety of applications including but not limited to generating power or actuating devices downhole. It may be beneficial to control the rotational speed of the turbine 207B to better meet requirements at a given time.

The plate 301B may be part of an actuator 204B such as a gear system or motor that actuates rotational movement. Alternatively, the plate 301B may hold the flow guide 205B stationary. A downhole processing unit disposed within the drill string (see FIG. 2) or surface processing unit (see FIG. 1) may be in communication with the plate 301B through the actuator 204B. Rotating the plate 301B may cause the vanes 306B to flex and bend such that a downwash angle of the drilling fluid may change below the at least one flow guide 205B. The flexible vanes 306B of the flow guide 205B may also restrict the rotational movement of the plate 301B.

FIGS. 4a and 4b illustrate the portion of an embodiment of a drilling assembly 103B of FIG. 3 and depict the flexible vanes 306B in various positions. In this embodiment, drilling fluid 410B is depicted flowing down the drill string and engaging the turbine 207B. Adjusting the flexible vanes 306B by rotating 454 the plate 301B flexes the flexible vanes 306B and changes the downwash angle that the drilling fluid 410B will engage the turbine 207. Changing the downwash angle causes the turbine 207B to travel at different speeds based upon the rotation 454 of the plate 301B. This method is used to slow down or speed up the turbine 207B or to increase or decrease the torque from the turbine 207. FIG. 4a depicts the plate 301A having no torque applied to it. In this orientation the vanes 306B are not flexed or bent. The drilling fluid 410 may flow past the vanes 306B nearly uninterrupted. The drilling fluid 410B may go on to exert a force on the turbine 207B by generating lift as it passes the turbine 207B. In FIG. 4b the plate 301B has a torque applied to it rotating the plate such that the vanes 306B are flexed. The flexed vanes 306B change the downwash angle of the drilling fluid 410B. The drilling fluid 410B engages the turbine 207B at an angle. The turbine 207B turns faster in this case due to increased lift than it would in the case depicted in FIG. 4a.

FIG. 5 depicts a diagram of a portion of an embodiment of a drilling assembly 103C comprising at least one flow guide

205C, a turbine 207C, and a generator 572C. In this embodiment the rotation of the turbine 207C actuates the generator 572C creating electrical power. The at least one flow guide 205C may be controlled by a feedback loop that is driven by the output voltage of the generator 572C. In one embodiment, the feedback loop positions the at least one flow guide 205C in such a way as to prevent the generator 572C from creating either too little power or too much power. Excess power created by the generator 572C may turn into heat which can adversely affect downhole instruments and too little power may prevent downhole instruments from operating.

In another embodiment, the positioning of the at least one flow guide 205C is set by an uphole user. An uphole user may set the position of the at least one flow guide 205C based upon a flow rate of drilling fluid entering the drilling assembly 103C, based upon a desired power output, or based upon some other desired parameter.

FIG. 6 depicts a portion of an embodiment of a drilling assembly 103D having an actuator 204D and at least one flow guide 205D. In this embodiment the at least one flow guide 205D is a rigid fin 503D. The fin 503D attaches to the drill string through a pivot point 504D. The actuator 204D in this embodiment is a plate 301D with slots 501D disposed around its circumference. The slots 501D are adapted to receive tabs 502D disposed on the fins 503D. The actuator 204D controls the fins 503D by rotating the plate 301D such that the tabs 502D engaged within the slots 501 cause the fins 503D to rotate on their pivot point 504D. The rotated fins 503D cause drilling fluid to change the angle at which it engages a turbine (not shown).

FIG. 7 is a diagram of an embodiment of a drilling assembly 103E having a turbine 207E, an actuator 204E, and at least one flow guide 205E. The flow guides 205E in the embodiment of FIG. 7 are fins 503. In this embodiment the actuator 204E comprises a rack 601E and pinion 602E. The rotation of the rack 601E causes the fins 503E to rotate around a pivot point 504E. The rotated fins 503E change the angle at which drilling fluid engages the turbine 207E thereby changing the rotational speed of the turbine 207E.

FIG. 8 is a depiction of another embodiment of a drilling assembly 103F having a turbine 207F, an actuator 204F and at least one flow guide 205F. In this embodiment the actuator 204F is a slider 701F. The slider 701F is disposed radially around a central axis of the drilling assembly 103F. The actuator 204F includes a motor, a pump, a piston, at least one gear, or a combination thereof, adapted to move the slider 701F parallel to the central axis of the drilling assembly 103F. The slider 701F has at least one flange 702F. The flow guide 205F is a fin 503F connected to the drill string at a pivot point 504F. The flow guide 205F further includes a lip 703F. The flange 702F of the slider 701F is adapted to fit on the lip 703F of the flow guide 205F. As the slider 701F moves towards the flow guide 205F the flange 702F exerts a force on the lip 703F causing the fins 503F to rotate. The rotated fins 503F change the angle at which drilling fluid engages the turbine 207F, generating additional lift, and changing the rotational speed of the turbine 207F.

FIG. 9 is a cross-sectional diagram depicting an embodiment of a drilling assembly 103G. In this embodiment the actuator 204G includes a solenoid valve 800G. The solenoid valve 800G includes a coil of wire 801G wrapped circumferentially around a central axis of the drilling assembly 103G. When the coil of wire 801G is electrically excited, a slider 701G is displaced such that a flow guide 205G is actuated. A preloaded torsion spring 802G may then return the flow guide 205G to an original position after the solenoid valve 800G disengages.

FIGS. 10a and 10b depict another embodiment of a drilling assembly 103H having a turbine 207H, an actuator 204H, and a flow guide 205H. The drill string assembly 103H has a plurality of turbines 207H. In this embodiment, the flow guide 205H is a funnel 905H. As the funnel 905H is axially translated it alters the flow space across the turbines 207H. As the funnel 905H restricts the flow space across the turbines 207H the drilling fluid velocity increases thus increasing the rotational speed of the turbines 207H.

The funnel 905H may be axially translated by means of a Venturi tube 910H. The Venturi tube 910H has at least one constricted section 915H of higher velocity and lower pressure drilling fluid and at least one wider section 920H of lower velocity and higher pressure drilling fluid. The Venturi tube 910H also has at least one low pressure aspirator 930H and at least one high pressure aspirator 940H. The at least one low pressure aspirator 930H that may be opened by at least one low pressure valve 935H and the at least one high pressure aspirator 940H may be opened by at least one high pressure valve (not shown). When the high pressure aspirator 940H is opened and the low pressure aspirator 930H is closed, the drilling fluid flows from the bore 208H to a chamber 950H. A piston element 955H attached to the funnel 905H and slidably housed within the chamber 950H forms a pressure cavity. As drilling fluid flows into the chamber 950H the pressure cavity expands axially translating the funnel 905H. (See FIG. 10a) If the low pressure aspirator 930H is opened and the high pressure aspirator 940H is closed, the drilling fluid flows from the pressure chamber 950H to the bore 208H. As drilling fluid flows out of the chamber 950H the pressure cavity contracts reversing the axial translation of the funnel 905H. (See FIG. 10b)

FIG. 11 illustrates an embodiment of a flow guide 205J in the form of a funnel 905J. In this embodiment the funnel 905J may be axially translated by means of at least one motor 1001J. The motor 1001J is in communication with a rack 1005J and pinion 1010J. The rack 1005J is connected to the funnel 905J and the pinion 1010J is a worm gear. As the pinion 1010J is rotated by the motor 1001J the rack 1005J and funnel 905J are axially translated.

FIGS. 12a and 12b illustrate an embodiment of a turbine 207K having at least one turbine blade 1107. The turbine blade 1107 is aligned along an initial vector 1110. The turbine blade 1107 may rotate a given angle 1115 to a subsequent vector 1120. The given angle 1115 may remain the same for several rotations of the turbine blade 1107 or the given angle 1115 may vary for different rotations. Rotation of the turbine blade 1107 from the initial vector 1110 to the subsequent vector 1120 may alter the rotational speed of the turbine 207K.

Whereas the present invention has been described in particular relation to the drawings attached hereto, it should be understood that other and further modifications apart from those shown or suggested herein, may be made within the scope and spirit of the present invention.

What is claimed is:

1. A method for adjusting the rotation of a turbine disposed in a through bore of drill string assembly, the through bore having at least one flow guide having a plurality of adjustable vanes disposed therein, the method comprising the steps of: providing a drilling fluid through said through bore, said drilling fluid flowing past said plurality of vanes and past said turbine; positioning said plurality of vanes at a first orientation, said first orientation causing drilling fluid flowing past said plurality of vanes to have a first downwash angle proximate said turbine;

adjusting said position of said plurality of vanes to a second orientation causing said drilling fluid passing said plurality of vanes to have a second downwash angle proximate said turbine; and
wherein said rotation of said turbine is dependent upon said downwash angle proximate said turbine.

2. The method of claim 1, wherein first downwash angle corresponds to a greater rotation of said turbine than a rotation of said turbine corresponding to said second downwash angle.

3. The method of claim 1, wherein said adjusting said position of said plurality of blades changes a torque of said turbine.

4. The method of claim 1, wherein said adjusting said flow guide is controlled by a downhole telemetry system.

5. The method of claim 1, wherein said drill string assembly includes a processing unit, the method further comprising a step of sending a command signal from said processing unit to said flow guide causing said flow guide to adjust said position of said plurality of vanes.

6. The method of claim 1, wherein said adjusting said position of said plurality of vanes is controlled by a feedback loop.

7. The method of claim 6, wherein said drill string assembly includes a generator powered by said turbine, and wherein said feedback loop is controlled by a voltage output from said generator.

8. The method of claim 6, wherein said feedback loop is controlled by a rotational velocity of said turbine.

9. The method of claim 6, wherein said feedback loop is controlled by a torque of said turbine.

10. The method of claim 6, wherein said feedback loop is adjustable by an uphole computer.

11. The method of claim 1 wherein said drill string assembly includes a hammer mechanically coupled to said turbine, wherein an actuation of the hammer is changed by adjusting the rotation of said turbine.

12. The method of claim 11, wherein said changing of the actuation of the hammer includes changing a frequency of said actuation of said hammer.

13. The method of claim 11, further comprising communicating uphole through said actuation of said hammer.

14. The method of claim 13, wherein said hammer impacts an object creating an acoustic wave and said acoustic wave is used to transmit data uphole.

15. The method of claim 14, wherein said object is an earthen formation.

16. The method of claim 14, wherein said object is a surface of said downhole drill string assembly.

17. The method of claim 14, further comprising the step of changing a pressure of said drilling fluid within said through bore of said downhole drill string assembly through actuation of said hammer to transmit data uphole.

18. The method of claim 14, further comprising vibrating said downhole drill string assembly through actuation of said hammer to transmit data uphole.

19. A downhole drill string assembly comprising:
a tubular body having a longitudinal bore adapted to receive a drilling fluid;
a bore there through to receive drilling fluid;
a turbine disposed within said longitudinal bore and adapted to be driven by said drilling fluid;
at least one adjustable flow guide disposed within said bore, said flow guide having a plurality of adjustable vanes adapted to selectively alter a velocity of said drilling fluid proximate said turbine; and
a hammer element in mechanical communication with said turbine.

20. A downhole drill string assembly comprising:
a tubular body having a longitudinal bore adapted to receive a drilling fluid;
a bore there through to receive drilling fluid;
a turbine disposed within said longitudinal bore and adapted to be driven by said drilling fluid;
at least one adjustable flow guide disposed within said bore and adapted to selectively alter a velocity of said drilling fluid; and
a feedback loop component in communication with said flow guide.
